[57] CLAIM

The ornamental design for a window shade pull, as
shown and described.

DESCRIPTION

FIG. 1 is a top plan view of a window shade pull showing
my new design;

FIG. 2 is a right end elevational view thereof; the oppo-
site end is a mirror image;

FIG. 3 is a front elevational view thereof; and

FIG. 4 is a rear elevational view thereof.

The bottom view is identical to that seen in FIG. 3.

FIG. 1.

FIG. 2.

FIG. 3.

FIG. 4.
